METHOD OF AND MEANS FOR VENTILATING
THREAD PROCESSING APPARATUS

Louis S. Fryer, Cleveland, and Richard F. Bergmann, Lakewood, Ohio, assignors to Industrial Rayon Corporation, Cleveland, Ohio, a corporation of Delaware

Application December 20, 1941, Serial No. 423,826

11 Claims. (Cl. 18—8)

The instant invention relates to methods of and means for ventilating apparatus for the production and processing of thread or the like, especially artificial silk thread. More particularly, the invention relates to an improved method of and means for ventilating such apparatus from a point above the spinning section thereof. For convenience, the invention will be described hereinafter in connection with a machine devoted to the manufacture of multiple filament viscose artificial silk thread according to a process generally similar to that shown, described and claimed in Knebusch et al. Patent No. 2,225,642.

In apparatus of the type disclosed in said patent, operations are classifiable into three main classes; namely, spinning, processing, and finishing the thread.

Of these, the spinning operation is advantageously conducted toward the top portion of the apparatus. The processing of the thread, which takes place in the intermediate portion of the structure, involves the subjection of the thread to a plurality of individual treating operations varying in number according to the character of the product desired. The finishing operations, which include the steps of drying, twisting and packaging the thread, are accomplished to best advantage toward the lowermost portion of the apparatus.

In view of the fact that vapors are evolved in certain of the operations entering into the production of the thread, the desirability of ventilating the apparatus as a whole can be appreciated. At the same time, however, the maintenance of uniform processing conditions is important to the achievement of the fullest benefits of the apparatus. In these respects the present invention is particularly advantageous, more especially in that it insures the continuance of uniform atmospheric conditions in the vicinity of the apparatus. Moreover, it makes possible a distribution of fresh air among the several operating levels of the machine, as may be desired to produce most effective results.

In the drawings, Figure 1 represents a partial side elevation of apparatus embodying the invention, while Figure 2 is a sectional elevation taken along line 2—2 of Figure 1.

In the illustrated apparatus, threads *a* are formed by the extrusion of viscose from spinnerets 5 into a coagulating bath 6 contained in spin trough 7. After having been withdrawn from bath 6, each thread *a* passes through a suitable guide 8 to a thread-advancing reel 10 of

cantilever construction. Each reel 10, one of which is provided for each thread *a*, is disposed so that its supported end is located directly above spinneret 5 while its unsupported end, from which said thread *a* is discharged, extends beyond the lateral limits of spin trough 7.

Thread *a* is not subjected to the action of any added processing liquid on reel 10, upon which coagulation is permitted to proceed more nearly to completion.

10 After its discharge from reel 10, thread *a* passes downward through a tubular passageway 9, which serves as a protection for said thread. At the lowermost end of passageway 9, thread *a* is directed to the first of a series of reels 11 to 19, inclusive, to each of which the thread passes in sequence. Like reel 10, each of reels 11 to 19, inclusive, is adapted to accept the thread at its supported end, store it in a plurality of generally helical turns, and discharge it from its unsupported end.

15 Reels 11 to 19, inclusive, of each series are arranged in vertically stepped relation with the discharge end of each reel in apposite relation to 25 the receiving end of its successor so that thread may pass readily from one reel to another. The axes of the reels are substantially horizontally disposed; consequently, the discharge ends of all of the reels in each series extend in the same 30 direction. The several series of reels may be advantageously arranged in two inclined banks in the manner disclosed in the aforementioned Knebusch et al. Patent 2,225,642.

Mildly acidic liquids heated considerably above 35 room temperatures are applied to the thread on reels 11 and 12. Reel 13 is devoted to a desulphurizing operation. Reel 14 serves as a washing stage. The thread is bleached on reel 15, after 40 which it is washed on reel 16. An oil emulsion or other similar conditioning compound may, if desired, be applied to the thread on reel 17. No treating step is performed while the thread is stored upon reel 18, any excess liquid adhering to the thread being permitted to drip therefrom 45 before the thread passes to drying reel 19.

The processing liquids employed in the various treating operations are applied to the thread by means of distributors 22. Pipe 23 supplies the liquor from a suitable source (not shown) to distributors 22 associated with reels 11. Distributors 22 showering liquid upon the thread stored on each of reels 12 to 17, inclusive, are supplied with treating liquid from conduits 24, each of which is formed as an integral part of the collecting 50 trough 25 for the reel disposed immediately

above. Collecting troughs 25, which are of the type shown, described and claimed in Jordan Patent 2,226,497, serve to collect the liquid dripping from the reels and to direct it either to the sewer or to suitable recirculating means.

Drying reels 19 are similar to the various other reels in respect of mode of operation but are constructed after the manner of the reel shown, described and claimed in Torrence et al. Patent 2,217,716. Each is heated internally as, for example, by the circulation of a heated fluid through the interior of the reel. The heated fluid is supplied to and removed from the reel by means of a hollow drive shaft connected to conduits 26 and 27. Supply and drain pipes 29 and 30 extending longitudinally of the apparatus connect all reels 19 on the same side of the machine. An enclosure 32 surround each reel 19 access to the reel for threading up, inspection and the like being provided by a door 33 hinged to enclosure 32.

From the drying reels, threads *a* next pass to collecting means. It is advantageous to combine a twisting operation with the collecting step and to this end a conventional cap twister mechanism 34 may be employed. In the cap twister mechanism illustrated in the drawings, bobbin 35 is reciprocated within cap 37, which is mounted on the upper end of a stationary spindle 36. At the same time, bobbin 35 is rotated at a high speed by whirl 38. Any suitable means may be employed to actuate the cap twister mechanism, but that indicated generally by reference character 39, which actuating means are of the type shown in Bergmann et al. Patent 2,203,665, has been found to be particularly satisfactory.

Since the apparatus is of considerable height, it is convenient to divide the machine by platforms 53 and 56 into three operating levels. The uppermost level advantageously includes all that portion of the apparatus devoted to the production of the thread; that is to say, the spinning section. The intermediate level provides access to the processing section of the machine. The drying, twisting and collecting operations are reached from the floor level. Beams 54, secured to uprights 55 which are in turn fixed to supporting frames 48 of the machine structure, serve to carry platforms 53.

Similar platforms 56 are provided at the intermediate level to afford access to processing reels 11 to 18, inclusive. Platforms 56 are supported by spaced horizontal beams 57 fixed at one end thereof to uprights 58 secured by brackets 59 to supporting frames 48. Suitable uprights may be provided to support the other end of beams 57 and platforms 56 or, if preferred, similar members 58 and 59 associated with adjacent machines (not shown) on opposite sides of that illustrated may be employed to carry the other end of said platforms 56 and beams 57, thereby providing communication between adjacent machines.

As shown, the portion of the apparatus which includes the thread-forming means is substantially completely enclosed. Longitudinally extending hood 60 is mounted above trough 7, being supported by spaced uprights 62 which serve to carry said trough 7 and are fixed to frame 48. Uprights 62 also support an upper longitudinally extending track 63 on each side of the machine. A similar lower track 64 is mounted upon apron 65 extending along each side of spin trough 7. Upper and lower tracks 63 and 64 respectively cooperate to serve as

supporting means for sliding doors 66 and 67.

Doors 66 and 67, which overlap in the manner indicated in Figure 1, provide the operator or operators working on platform 53 with access to spinnerets 5, spin trough 7, reels 10 and other associated apparatus. After the leading end of the thread *a* has been manually withdrawn from bath 6, passed through guide means 8, threaded onto reel 10, and, upon its discharge from the unsupported end of reel 10, dropped through channel 9, doors 66 and 67 are closed. In the ordinary operation of the machine, these doors are kept closed.

Between hood 60 and plate 69 is an exhaust duct 68 extending from end to end of the machine as a whole. Connected to one end of said exhaust duct 68 is riser 70 which joins a main exhaust duct (not shown) to which is connected some suitable device, such as an exhaust fan, for maintaining a negative pressure in the system. Extending longitudinally of plate 69 and disposed directly above reels 10 are slots 72 which vary in width from one end of the duct to the other, being narrowest near the exhaust end and widest toward the opposite end thereof. Vapors from bath 6 and reels 10 enter slots 72 and are carried away to a suitable stack (not shown).

The space 20 between the oppositely extending banks of reels 11 to 19, inclusive, is substantially completely enclosed for the purpose of preventing entrance thereto of any vapors developed by the processing operations. End panel 73 and a like panel on the opposite end of the apparatus serve to close off the ends of the machine while the back portions of collecting troughs 25 and the rear walls of enclosures 32 housing drying reels 19 form the side walls of space 20. Flooring 74 and walls 75 complete the enclosure bounding space 20. A door 76 may be provided in one of the end panels 73 to provide access to the interior of the apparatus.

Ventilating ducts 77 disposed beneath platform 53 and extending the entire length of each side of the machine are associated with the intermediate level of the apparatus, from which they remove vapors generated in the vicinity of reels 11 to 18, inclusive. Slot 78, the width of which is adjustable in the manner shown, extends the full length of duct 77. By means of suitable connections 79 and 80, ducts 77 are tied into a common riser 82 which, through the main exhaust duct, maintains a negative pressure in ducts 77. In this manner is created an upward current of air across the two oppositely extending banks of reels 11 to 18, inclusive, thus carrying the vapors through slots 78 into ducts 77.

Ducts 77 are of varying width as indicated by side walls 83, 84, 85, the widest portions being adjacent the discharge ends thereof.

For the purpose of removing moist air from the enclosures 32 surrounding drying reels 19, a duct 86 extends longitudinally of and on each side of the apparatus to the rear of twisters 34. Through a series of suitable cross connections 87 and riser 88, ducts 86 connect to riser 82. As a result of the negative pressure maintained in duct 86, an air current is set up drawing air through louvres 89 in doors 33 of enclosures 32. Within enclosures 32 are air intaken means 90 registering with openings 92 in the floors of the respective enclosures 32, such openings 92 communicating with duct 86.

Suitable dampers control the flow of air in the

several ducts and risers. Dampers 93 and 94 in connections 79 and 80, respectively, and dampers 95 and 96 in risers 82 and 88, respectively, are provided for this purpose. A detailed description of the construction and mode of operation of ducts 68, 77, 86, together with their associated risers, cross connections, dampers, etc., is contained in copending application Serial No. 309,834, filed December 18, 1939, by Richard F. Bergmann.

The present invention involves the further provision in apparatus of the character described of means adapted to supply a constant flow of fresh air over each of the working faces of the machine. Efficient operation of the apparatus as a whole is achieved by introducing the fresh air supply at a point substantially directly above the machine itself. The means to accomplish this purpose may take any of several suitable forms, but that shown in the accompanying drawings is one which has been found to be particularly advantageous.

In this embodiment of the invention, supply duct 97 carrying the fresh air supply is mounted atop hood 60, being supported thereabove by cross members 98 in such manner as to provide a space 99 for insulation. Supply duct 97 extends from one end to the other of hood 60. To one end of supply duct 97 is connected a riser 100 and duct 102 the latter of which communicates with a main feeder duct (not shown) supplying fresh air to duct 97 and similar ducts associated with adjacent machines in the same room.

Fitted into circular ports 110 in the arched top 103 of supply duct 97 are fresh air outlets 104, such outlets being disposed at intervals along the supply duct. Each outlet 104 is so equipped with baffles 105 secured to the interior of annular member 106 as to be capable of dividing and directing the air passing through ports 110. Part of the air leaving supply duct 97 through outlet 104 strikes baffles 105 and is diverted through opening 107 below annular member 106. The remaining portion passes to one side or the other of baffles 105, escaping through opening 108 of outlet 104 between annular member 106 and dome 109.

Suspended in the interior of supply duct 97 immediately below each port 110 is a deflector 113. Deflectors 113, each of which comprises a plurality of curved horizontal vane members 114 arranged in parallel relation, are disposed in each case at an angle to top 103 of supply duct 97, being secured thereto by means of hinged mounting 111. Curved vane members 114 are positioned with their concave surfaces facing into the flow of air through supply duct 97. Depending upon the degree of angularity with which deflector 113 is mounted with respect to supply duct 97, more or less of the air passing therethrough will strike curved vane members 114 and be diverted toward outlet 104. Deflectors 113 are preferably adjusted so as to cause equal quantities of air to pass through outlets 104.

Experimentation has shown that a distribution of the air passing through each of outlets 104 according to which approximately 30 to 50% of the total is diverted through opening 107 with the balance discharged at opening 108 provides satisfactory operating conditions. With this distribution, air passing through opening 107 flows down over arched top 103, the external surface of hood 60, and doors 66 and 67 to platforms 53, thus continually supplying fresh air to the operator or operators attending the spinning section of the machines. After reaching platforms 53, the air

spills downward over the edges of the platforms to processing reels 11 to 18, inclusive.

That portion of the fresh air supply passing through opening 108 is directed outward and downward toward the floor level, mingling with that portion of the air from opening 107 which, as previously explained, spills over the edges of platforms 53. Part of this air finds its way through louvres 89 in door 33 to enclosure 32 surrounding drying reel 19. The remainder of the air supply from opening 108 flows upward in the form of a blanket across the operating face of the machine; i. e., the section including processing reels 11 to 18, inclusive, passing thence into ducts 77. Air thus passing into ducts 77 is filtered, purified and returned to supply duct 97 for re-use.

In this manner a constant flow of fresh air is supplied to the various stages of the apparatus.

The apparatus hereinabove described is illustrative of the principles of the invention. It may, however, be modified extensively without departing from the inventive concept. Outlets 104 in supply duct 97 may, for example, take the form of a series of vents or louvres located in the sides of said duct rather than on top of it without in any way affecting the operation of the apparatus.

It is intended that the patent shall cover, by suitable expression in the amended claims, whatever features of patentable novelty reside in the invention.

What is claimed is:

1. The method of maintaining a constant flow of fresh air across the operating face of thread-processing apparatus characterized by a plurality of operating levels comprising the steps of providing a constant supply of fresh air, discharging the air substantially directly above the uppermost operating level of the apparatus, distributing at least a portion of the supply of fresh air to each of the several operating levels comprising the apparatus, and withdrawing air at each of the several operating levels.

2. The method of maintaining a constant flow of fresh air across the operating face of thread-processing apparatus characterized by a plurality of operating levels and withdrawing means associated with each level comprising the steps of providing a constant supply of fresh air, discharging the air substantially directly above the apparatus, apportioning the fresh air supply to each of the several operating levels, directing each allotted portion of the supply of fresh air downwardly over one of the operating levels comprising the apparatus, and withdrawing air at each of the several operating levels.

3. Ventilating means for thread-processing apparatus characterized by a plurality of operating levels comprising a supply duct mounted on top of the apparatus providing a constant supply of fresh air; means in said supply duct operating to discharge therefrom at least a portion of the air passing therethrough; and means associated with said discharge means for apportioning the air between the several operating levels of the apparatus.

4. Ventilating means for thread-processing apparatus characterized by a plurality of operating levels comprising a supply duct mounted on top of the apparatus providing a constant supply of fresh air; means in said supply duct operating to discharge therefrom at least a portion of the air passing therethrough and to apportion it between the several operating levels of the apparatus; and means adjacent each of said operating

levels for removing vapors developed in the various operations performed on the apparatus.

5. Ventilating means for a thread-processing apparatus characterized by a plurality of operating levels comprising a supply duct extending longitudinally of the apparatus as a whole and mounted on top of the apparatus providing a constant supply of fresh air; means in said supply duct operating to discharge therefrom at least a portion of the air passing therethrough; and means associated with said discharge means for apportioning the air between the several operating levels of the apparatus.

6. Ventilating means for continuous processing apparatus characterized by a plurality of operating levels at each of which thread is submitted to treatment comprising a supply duct providing a constant supply of fresh air mounted above the uppermost operating level of the apparatus; means in said supply duct for discharging part of the air passing therethrough; means for apportioning the discharged air to the several operating levels of the apparatus; and means associated with each of the operating levels of the apparatus for withdrawing air from the various treating operations, whereby a constant flow of fresh air is maintained across the entire operating face of the apparatus.

7. Ventilating means for continuous processing apparatus characterized by a plurality of operating levels comprising a supply duct mounted upon the uppermost portion of the structure providing a constant supply of fresh air; a plurality of discharge means disposed in said supply duct and arranged at spaced intervals along the longitudinal axis thereof, each of said discharge means operating to discharge part of the air passing through said supply duct and to distribute it to the several operating levels of the apparatus; and means associated with each of said operating levels for removing vapors resulting from the treating operations.

8. The method of ventilating thread-processing apparatus characterized by one or more operating levels comprising introducing a supply of fresh air at a point on the apparatus above the uppermost operating level, discharging at least a portion of the air supply at each of a plurality of spaced points along the longitudinal axis of the apparatus, and withdrawing air from said uppermost operating level whereby a constant flow of fresh air is maintained in the form of a blanket extending along the uppermost operating level from one end of the apparatus to the other.

9. Ventilating means for continuous processing apparatus characterized by a plurality of operating levels comprising a supply duct mounted upon the uppermost portion of the structure providing a constant supply of fresh air; a plurality of exhaust ports disposed in spaced relation in one wall of said supply duct; deflecting means disposed within said supply duct adjacent each of said exhaust ports for directing part of the air passing through said supply duct through said exhaust ports; and discharge means disposed exteriorly of said supply duct registering with said exhaust ports for diverting portions of the air supply emerging from said exhaust ports to the several operating levels of the apparatus.

10. Ventilating means of the character described in claim 9 in which means are provided for adjusting the deflecting means so that a substantially equal flow of air passes through each of said exhaust ports.

11. Ventilating means of the character described in claim 9 in which means are provided for controlling the output of each of the discharge means so that from 35 to 55% of the air passing through said discharge means is diverted directly downward over the uppermost operating level.
